US00D941619S

(12) United States Design Patent (10) Patent No.: US D941,619 S
(45) Date of Patent:  *Jan. 25, 2022

(54) HALL TREE

(71) Applicant: WALKER EDISON FURNITURE COMPANY LLC, Salt Lake City, UT (US)

(72) Inventors: Matthew Davis, Murray, UT (US); Brad Bonham, Draper, UT (US); Richard A. Packer, Kaysville, UT (US)

(73) Assignee: Walker Edison Furniture Company LLC, West Jordan, UT (US)

(*) Notice: This patent is subject to a terminal disclaimer.

() Term: 15 Years

(21) Appl. No.: 29/694,776

(22) Filed: Jun. 13, 2019

Related U.S. Application Data

(63) Continuation of application No. 29/677,745, filed on Jan. 23, 2019, now Pat. No. Des. 923,370.

(57) CLAIM

The ornamental design for a hall tree, as shown and described.

DESCRIPTION

FIG. 1 is a front perspective view of a first embodiment of a hall tree showing the new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right elevation view thereof;

FIG. 7 is a left elevation view thereof;

FIG. 8 is another front perspective view of a second embodiment of a hall tree showing the new design;

FIG. 9 is a front elevation view thereof;

FIG. 10 is a back elevation view thereof;

FIG. 11 is a top plan view thereof;

FIG. 12 is a bottom plan view thereof;

FIG. 13 is a right elevation view thereof; and,

FIG. 14 is a left elevation view thereof.

The broken lines in the drawings are for the purpose of illustrating portions of the hall tree that form no part of the claimed design.

1 Claim, 8 Drawing Sheets
